UNITED STATES PATENT OFFICE.

FRANK L. THOMAS, OF BUFFALO, NEW YORK, ASSIGNOR TO DONNER STEEL COMPANY, INC., OF BUFFALO, NEW YORK.

REINFORCING BAR FOR CONCRETE CONSTRUCTION.

Application filed December 1, 1922. Serial No. 604,201.

To all whom it may concern:

Be it known that I, FRANK L. THOMAS, a citizen of the United States, residing at Buffalo, in the county of Erie and State of New York, have invented a new and useful Improvement in Reenforcing Bars for Concrete Construction, of which the following is a specification.

This invention relates to improvements in metal bars of the kind adapted for use in reinforced concrete construction.

Many types of metal bars have heretofore been used in connection with reinforced concrete constructions, and some of these types are well adapted for one kind of work and other types may be used to better advantage on other work. A rectangular, oblong bar is desirable for the reason that its surface area per unit of length is greater than that of a square or round bar, and therefore is more firmly bonded to the surrounding concrete. Rectangular, oblong bars, however, as well as oval bars, are objectionable in that they may be easily bent in one plane only. Square bars are more desirable than rectangular bars in that they can be readily bent in two planes, but have less surface area, and round bars can be readily bent in any direction, but have still less surface area for a given cross sectional area than either square, oval or rectangular bars. Square and rectangular bars, and some types of deformed bars also have the disadvantage that the corners thereof form re-entrant angles in the surrounding concrete, which start cracks in the concrete. Bars of other shapes have been devised with the view of overcoming the objections to the round, oval, square and rectangular bars, but these bars embody other defects when used in concrete construction or are difficult to roll, so that these bars are expensive to produce.

The objects of this invention are to provide a bar of this kind which is so formed that when used in connection with concrete construction, the bar is superior to rectangular, square or oval bars now used, and also embodies certain improvements over bars of round or circular cross section, as well as over bars of other shapes; also to provide a bar of this kind which is superior to bars heretofore provided in respect to the cost at which the bar can be manufactured, especially in that my improved

bar can be manufactured with less loss due to imperfections, and from rolls that are more easily prepared and maintained in operation; also to improve the construction of reenforcing bars in the other respects hereinafter specified.

In the accompanying drawings:

Figs. 1 and 2 are side views of a reenforcing bar embodying the invention.

Figs. 3 and 4 are sections thereon on lines 3—3 and 4—4, Fig. 1.

Fig. 5 is a perspective view of a portion of a reenforcing bar.

The core A of the bar embodying the invention is uniform in cross section, and the cross section approximates a polygon, the bar having an even number of sides greater than four. In the particular embodiment of the invention shown in the drawings, a bar is shown having a six-sided core. The cross section of the core of the bar somewhat resembles a star with rounded points, or a hexagon with rounded points and concaved sides, inasmuch as, the edges of the core of the bar are rounded as shown at a, and the sides or portions between edges are concaved or fluted, as at a'. The concaved sides or fluted portions, however, are shallow so that the concrete will readily flow into the concave sides and so that the bar can readily be bent in all planes passing through the axis of the bar. By rounding the portions a of the bar, no re-entrant angles are formed which cause cracking of the concrete. The cross section of the core of the bar, as shown particularly in Figs. 3 and 4, is of such form that the perimeter thereof is approximately the same as the perimeter of a square of the same area. Consequently, a bar of this cross section has the same surface exposed for bonding with the surrounding concrete as a square bar, but overcomes the objection of the re-entrant angles of the square bars and also overcomes the objections to square bars that they are only capable of being bent in two planes.

The bar is also provided with two series of transverse ribs B and B', each of the ribs extending half way round the bar. The series of ribs B is arranged on one side of the bar and the ribs B' are arranged on the other side thereof, and the two series are so arranged that a rib on one side of the bar is intermediate between adjacent

ribs of the other side of the bar, thus forming a staggered arrangement of the ribs. These ribs B and B' are so arranged that the ends of the ribs merge into the longitudinal, rounded edge portions *a* at diametrically opposite sides of the bar, and the transverse ribs preferably extend slightly beyond the other longitudinal edge portions *a*. When the concrete is poured around the bar described, the ribs become embedded in the concrete so that longitudinal movement of the bar in the concrete is prevented.

The bar described, in addition to its advantages when used in connection with reinforced concrete construction, also has decided advantages from the standpoint of its production in a rolling mill. In the first place, the rolls used in connection with the manufacturing of this bar can be very easily manufactured, since all of the machining of the rolls can be done by milling cutters, and no hand work of any kind is required on the rolls. The rolls are so made that one of the series of ribs is formed by one roll while the ribs of the other series are formed by the other roll, and by arranging these ribs in staggered relation, as shown, an accurate adjustment of the rolls with regard to each other in such a manner that the rib-forming portions of one roll always register in a definite relation to the rib-forming portions of another roll, is not necessary. A variation in the location of the ribs of one side of the bar with reference to the ribs of the other side is of no importance. Consequently, in the original machining of the rolls as well as in the re-cutting of the rolls after they become worn, no particular attention need be paid to having the rib-forming portions of one roll very accurately positioned with reference to the corresponding portions of the other roll. Actual experience has shown that a greater tonnage of bars of the kind described can be produced from a set of rolls than of any other bars now on the market. Due to the shape of the core of the bar described, the rolls grip the bar in such a manner that there is very little or no tendency of the bar to twist when leaving the rolls, which is a common source of trouble in most deformed bars, so that the loss due to this imperfection in rolling is reduced to a minimum. Also, due to the shape of the core of the bar, it is easier to get and to maintain the true section when rolling than with other deformed bars heretofore used, whereby a greatly increased production is obtained.

The bar described embodies all of the good features of bars of round and square cross section, and overcomes all of the objections of these bars. Furthermore, the material in the core of the bar is uniformly and compactly arranged about the longitudinal axis

of the bar so that every part of the core is employed in resisting tensional or compression stresses. The longitudinal, rounded edges do not project far enough from the concaved portions of the sides of the bar to crack or buckle when the bar is bent, and consequently the bar develops at all times and under all conditions of use the full, tensile strength of the metal of the core. Furthermore, the shape of the bar is such that the same cannot be twisted in the concrete when subjected to torsional stresses, as sometimes happens if round bars are used. The bar may also be easily bent in any direction with reference to its longitudinal axis. The arrangement of the metal in the core about the longitudinal axis is such that the bar is stiffer under compressive strains than any other existing types on the market and is therefore better adapted for reinforcing columns and for other reinforced concrete work than other bars now in use.

I claim as my invention:

1. A reinforcing bar for concrete construction including a core having a cross section simulating a polygon of more than four sides, the edge portions of the core being rounded and the sides being concaved so that the periphery of the cross section will be greater than that of the polygon of corresponding cross-sectional area, and two series of transverse ribs which are arranged at opposite sides of the bar and which are substantially semicircular in form and which extend across the space between adjacent longitudinal edge portions of the core, the ribs of the series being arranged in staggered relation to each other.

2. A reinforcing bar for concrete construction including a core, the cross-section of which simulates a polygon, the edges of the core being rounded and the portions of the core between the edges being provided with shallow depressions to provide a core which has a large surface area and which resists twisting when embedded in concrete, and two series of transverse ribs arranged at opposite sides of the core, the ends of the transverse ribs merging into diametrically opposite longitudinal edge portion of the bar, the ribs of one series being arranged in staggered relation to the ribs of the other series.

3. A reinforcing bar for concrete construction including a core, the cross section of which simulates a polygon having an even number of sides greater than four, the edges of the core being rounded and the sides being concaved, forming a core with a wave-like periphery, and two series of transverse ribs, the ribs of each series encircling half of the bar and the ribs of one series being staggered with regard to the ribs of the other series.

FRANK L. THOMAS.
